 3 Claims. (Cl. 156—54)

This invention relates to coaxial electric cables.

According to the present invention there is provided a coaxial cable which includes an inner conductor, an outer conductor and electrical insulating material supporting the inner conductor and bonded to the outer conductor.

Further according to the present invention there is provided a method of manufacturing a coaxial cable which includes the steps of placing electrical insulation around an inner conductor, placing an outer conductor round the insulation and bonding the electrical insulation to the outer conductor.

In the accompanying drawings which illustrate embodiments of the present invention.

FIG. 1 is a perspective view of a coaxial cable with a portion of the outer conductor removed,

FIG. 2 is a similar perspective view to that shown in FIG. 1, but of a different coaxial cable,

FIG. 3 is a perspective view of a metal strip, with pieces of insulation, disposed thereon, and

FIG. 4 is a perspective view of a coaxial cable having the metal strip in FIG. 3 applied as an outer conductor, and

FIG. 5 is a perspective view of another metal strip, with pieces of insulation.

Referring to FIG. 1, there is shown an inner conductor 1, cellular polythene insulating cylinders 2, and an outer conductor 3. The insulating cylinders 2 have a radial slit 4 and on the inner surface of the outer conductor 3 there is a polythene coating 5 which is bonded to the insulating cylinders 2.

The coaxial cable is manufactured by extruding cellular polythene insulating material in a continuous length of cylindrical shape, cutting it into the cylinders 2, and then cutting the slits 4 in the cylinders 2. The cylinders 2 are then placed on the inner conductor 1 at spaced intervals along its length by pressing the inner conductor 1 in the slots 4. The outer conductor 3 in the form of a polythene coated metal strip is longitudinally folded round the cylinders 2 with the polythene coating 5 on the inside. The outer conductor 3 is then heated to weld the cylinders 2 to the polythene coating 5.

If desired the cylinders 2 may be replaced by continuous solid or cellular polythene insulation which is extruded directly about the inner conductor 1. The outer conductor 3 may be formed by helically winding one or more polythene coated tapes round the cylinders 2.

In the embodiment shown in FIG. 2 like parts are designated with the same reference numerals as those in FIG. 1. The inner conductor 1 has spaced discs 6 of polythene on it instead of the cylinders 2 of cellular polythene. In the discs 6 there is a radial slit 7.

This alternative construction of coaxial cable is manu-

2

factured in a similar manner to the coaxial cable shown in FIG. 1, with the discs 7 bonded to the coating 5.

Referring to FIGS. 3 and 4 there is shown a metal strip 8 having a polythene coating 9 and pads 10 of cellular polythene bonded to the polythene coating 9. In FIG. 4 the metal strip 8 together with the pads 10 is shown being folded round an inner conductor 11. This forms a construction with an outer conductor 12 separated from the inner conductor 11 by the pads 10 which are bent to form cylinders round the inner conductor 11.

The pads 10 are cut from a strip of extruded cellular polythene and placed on the polythene coating 9. The assembly is then heated to bond the polythene coating 9 to the pads 10.

If desired strips of polythene may replace the pads 10 of cellular polythene. These polythene strips may cross the metal strip at right angles and so form discs round the inner conductor 11 when the metal strip 8 is folded round it. As shown in FIG. 5, the polythene strips 13 also may cross the metal strip 8 diagonally in such a manner that they provide a continuous helix round the inner conductor 11 with the ends of different strips in contact. With reference to FIGURE 5, ends A and B would interface, and ends C and D as well, forming a helical insulation about conductor 11 when metal strip 8 is folded.

In the embodiments described the outer conductor is bonded to the insulating material supporting the inner conductor by means of heating which causes fusion to take place between the insulating material and a layer of similar material on the inner surface of the outer conductor.

It is not essential for the two materials to be similar so long as they are capable of fusing together, and the layer of material need not be continuous between the pieces of supporting insulating material.

The supporting material need not be bonded to the outer conductor through the intermediary of a similar material. An adhesive layer may be applied directly to the inner surface of the outer conductor, and the supporting material may be bonded by means of this layer to the outer conductor. It is possible for the adhesive layer to be applied to the supporting material.

It is to be understood that the foregoing description of specific examples of this invention is not to be considered as a limitation on its scope.

What we claim is:

1. A method of manufacturing a coaxial cable comprising the steps of:
 bonding longitudinally spaced quadrangular pieces of thermoplastic insulating material to a longitudinal metal strip; and
 longitudinally folding said metal strip about an inner conductor so that said pieces of insulating material encircle and support said inner conductor.
2. A method as claimed in claim 1 in which the spaced pieces form cylinders at spaced intervals along the length of the inner conductor when applied thereto.
3. A method as claimed in claim 1 in which the spaced pieces form at least one continuous helix round the inner conductor when applied thereto.
